H. S. BLAKE

AIR CONTROL FOR OIL BURNERS

Filed Aug. 4, 1926

Patented Feb. 21, 1928.

1,660,032

UNITED STATES PATENT OFFICE.

HAROLD S. BLAKE, OF ATTLEBORO, MASSACHUSETTS.

AIR CONTROL FOR OIL BURNERS.

Application filed August 4, 1926. Serial No. 127,044.

This invention relates to an improved apparatus for burning liquid fuel such as hydrocarbon oils; and has for its object to provide means for causing the air to move with great velocity along the inner surface 5 of the air conduit until it is deflected at the discharge end with means for controlling the relative quantities of air along the upper and lower portions of the tube.

10 A further object is to locate a fire-deflecting device in a furnace and to direct a supply of air to the deflector from a blower also to provide a fuel pipe having a jet opening adjacent the tube opening so that the air and 15 the oil will mix and be ignited before being forced against the deflector member, means also being provided for controlling the direction of discharge of the fuel mixture so that the flame may be forced at a proper angle 20 into the deflector.

A still further object of the invention is the provision of a rockable valve seat in the air tube and a valve to cooperate with the seat whereby the seat may be rocked or 25 tipped to control the direction of discharge of air and oil from the end of the tube.

With these and other objects in view, the invention consists of certain novel features of construction, as will be more fully described, and particularly pointed out in the 30 appended claims.

In the accompanying drawings:

Figure 1 is a side elevation showing my improved apparatus.

Figure 2 is a plan view of the same.

35 Figure 3 is an enlarged sectional elevation showing the air tube with the oil supply passing therethrough, a valve and the rocking valve seat.

Figure 4 is a sectional end view on line 40 4—4 of Figure 3.

Figure 5 is a fragmental side elevation showing the valve operating cam and the valve ring.

45 Figure 6 shows a fragmental portion of the air tube and showing the valve ring and the cam for rocking the ring on its pivotal axis for changing the direction of the flow of air to the tube end.

Figure 7 is a rear view of the blower 50 showing the oil pipe and its bushing.

It is found in the practical operation of liquid fuel burners of this character, of advantage to position the deflecting member in the fire-pot of a furnace for the purpose 55 of controlling and directing the heat from

the burning flame; also to provide a tube having a discharge outlet adjacent this deflector, the opposite end of the tube being connected with an air blower and through 60 this tube I extend an oil pipe having a jet opening practically flush with the opening in the discharge tube, whereby the air from the tube and the oil from the jet are caused to mix and be ignited and the flame forced 65 against the deflector, and it is found in practice necessary to provide some means for controlling and directing the flame to impinge at the required angle against the deflecting member; and in order to accomplish 70 this in a simple and effective way, I have provided a conical valve in the tube to deflect the air and move it along the inner surface of the tube and have pivotally mounted a valve seat about the valve to be 75 tipped or rocked relative to the valve and so control the angle of the flame jet as it is projected against the deflector. In other words, where the draft is strong in the furnace, it is necessary that the jet be directed 80 downwardly into the deflector in order to hold the fire therein, while under a lighter draft a less angle of the jet is required, that is the angle of the jet may be regulated to 85 suit the different conditions under which the apparatus is called upon to operate; and the following is a detailed description of the present embodiment of my invention and showing one construction of mechanism by 90 which these advantageous results may be accomplished:

With reference to the drawings, 10 designates the deflector member which is herein shown as being in somewhat of a pear or spoon shape and is secured in the fire-pot of 95 a furnace 11. The air is conducted to this fire-pot by means of a tube 12 from a blower 13 driven by a motor 14.

The inner end of this tube is provided with a head member 15 with a reduced discharge opening 16 and through the center of this tube below the blades of the fan I lead an oil supply pipe 17 from the supply tank 18, the inner end of this pipe being provided with a jet nozzle 19 for spraying the oil to mix with the air from the tube.

About this oil pipe 17 I have mounted a valve guide tube 20 which is supported on brackets 21 and on this guide tube I have mounted an endways slidable conical valve 110 22 which is pressed towards open position by a spring 23. This valve 22 has a conical

or flaring surface to cause the air to be deflected to the outer part of the air tube to move along its inner surface with great velocity until it reaches the discharge end of the tube where it is again deflected across the oil discharge opening. The air moves with such velocity along the inner surface of the air conducting tube that a partial vacuum is created at the center of the air tube about the oil supply.

The nozzle is mounted in the tube 20 to be withdrawn endways therefrom out through the bushed rear end of the blower 13 for inspection and repairs.

15 Cooperating with this valve is a valve seat ring 24 which is pivoted at 25 on its opposite sides to swing so as to control the extent of the valve opening at its upper and lower portions.

20 In order to rock this valve ring, I have provided a cam pin 26 having an eccentric pin 27 engaging the ring so that when this cam pin is rotated it swings the seat on its pivots 25 to produce unequal openings on the 25 top and bottom of the valve. In other words, when the ring is swung into position as illustrated in Figure 6, a wider opening is caused as at 28 on the under side of the valve and when swung to the opposite 30 position a wider opening will be formed on the upper side of the valve.

When it is desired owing to draft and other conditions in the furnace that the air and oil discharge shall be in a line with the 35 axis of the tube, the ring is held in a central or vertical position and the amount of air to be discharged through the tube is controlled by the positioning of the cam 30. In other words, if more air is required this cam 30 will be rotated through its stem 31 to permit the valve to open wider under action of its spring 23 and if less air is required this cam 30 will be rotated back to more nearly close the valve against its ring, but when it is 40 required to tip the jet which is projected from the end of the tube downwardly, it is necessary to operate the cam pin 26 to swing the valve ring and cause a wider opening on the upper side of the valve 22 45 which will cause the air to pass along the upper surface of the tube and then downward along the inclined surface 32 whereby by its force will bend the jet of air and oil downwardly to throw the flame at the proper angle into the deflector, to obtain the most 50 advantageous results.

By my improved construction of valve and ring in the air pressure tube any desired angle of the rise and fall of the jet, 55 may be obtained.

60 The foregoing description is directed solely towards the construction illustrated but I desire it to be understood that I reserve the privilege of resorting to all the mechanical 65 changes to which the device is susceptible,

the invention being defined and limited only by the terms of the appended claims.

I claim:

1. In a liquid fuel burner, a fire deflecting device located in the furnace, a blower, an air supply tube leading from the blower and having a discharge opening adjacent said deflector, a fuel supply jet adjacent the air discharge, and means for selectively directing the fuel mixture discharge into the deflector through a vertical range extending on both sides of the axis of the air tube. 75

2. In a liquid fuel burner, a fire deflecting device located in the furnace, a blower, an air supply tube leading from the blower and having a discharge opening adjacent said deflector, a fuel supply pipe extending through said tube and having a discharge opening adjacent that of the air tube, and means comprising a valve in the tube for inversely changing the quantity of the air discharge above and below the axis of the tube. 80

3. In a liquid fuel burner, a fire deflecting device located in the furnace, a blower, an air supply tube leading from the blower and having a discharge opening adjacent said deflector, a fuel supply pipe extending through said tube and having a discharge opening adjacent that of the air tube, a tiltable valve seat member in the tube, a valve cooperating with said seat, and means for tilting the seat relative to the valve. 85

4. In a liquid fuel burner, a tube having a discharge opening in the furnace for conducting air pressure thereinto, an oil supply pipe extending through the tube and having a jet discharge adjacent said air discharge, a pivotally mounted valve seat ring in said tube, a spring-pressed axially movable valve cooperating with said seat, means for retaining said valve in predetermined open position, and means for swinging said valve seat with respect to said valve. 90

5. In a liquid fuel burner, a blower, a tube for conducting air from the blower to a furnace, an oil supply having a discharging nozzle adjacent the end of said air conducting tube, and means in said tube for directing a greater quantity of air above or below its axial center as desired. 100

6. In a liquid fuel burner, a blower, a tube for conducting air from the blower to a furnace having a conically reduced discharging end, an oil supply having a discharging nozzle adjacent the end of said air conducting tube, and means in said tube for directing a greater quantity of air above or below its axial center as desired to permit of a deflection of the flame relative to the axis of the tube. 105

7. In a liquid fuel burner, a blower, a tube for conducting air from the blower to a furnace, an oil supply having a discharging nozzle adjacent the end of said air conducting 110

tube, a conical outwardly flaring valve in said tube being of a size and positioned to leave an annular passage between it and the tube to shunt the air outwardly against the inner surface thereof, and separate adjustable means cooperating with said valve for controlling said passageway.

8. In a liquid fuel burner, a blower, a tube for conducting air from the blower to a furnace having a conically reduced discharging end, an oil supply having a discharging nozzle adjacent the end of said air conducting tube, a conical outwardly flaring valve within said tube for deflecting the air outwardly to move along the inner surface of said tube with great velocity until it is deflected by the conical outer end of said tube, said conical valve being of a size and positioned to leave an annular passage between it and the tube, and separate adjustable means cooperating with said valve for controlling said passageway.

9. In a liquid fuel burner, a blower, a tube for conducting air from the blower to a furnace having a conically reduced discharging end, an oil supply having a discharging nozzle adjacent the end of said air conduct-

ing tube, a conical valve in said tube for deflecting the air outwardly to move along the inner surface of said tube with great velocity until it is deflected by the outer conical end of said tube, a valve seat ring adjacent said valve, means to pivotally mount said ring, and means to move the ring about its pivot to vary the relative quantities of air passing along the upper and lower side of said tube.

10. In a liquid fuel burner, a blower, a tube for conducting air from the blower to a furnace having a conically reduced discharging end, a conical valve in said tube for deflecting the air outwardly to move along the inner surface of said tube with great velocity until it is deflected by the outer conical end of said tube, a valve seat ring adjacent said valve, means to pivotally mount said ring, means to move the ring about its pivot to vary the relative quantities of air passing along the upper and lower side of said tube, and means to adjust said valve bodily relative to its valve seat.

In testimony whereof I affix my signature.

HAROLD S. BLAKE.
